UNITED STATES PATENT OFFICE.

FRANCIS J. TORRANCE, OF PITTSBURG, PENNSYLVANIA.

DESIGN FOR A BATH-TUB.

SPECIFICATION forming part of Design No. 17,902, dated November 22, 1887.

Application filed September 8, 1887. Serial No. 249,180. Term of patent 7 years.

To all whom it may concern:

Be it known that I, FRANCIS J. TORRANCE, a citizen of the United States, residing at Pittsburgh, in the county of Allegheny and State of Pennsylvania, have invented certain new and original Designs for Bath-Tubs; and I do hereby declare the following to be a full, clear, and exact description of the invention, reference being had to the accompanying drawings, which form part of this specification.

My invention relates to a design for bath-tubs; and it consists in the novel configuration hereinafter described and claimed, and illustrated in the accompanying drawings, where-

15 in—
Figure 1 is an end elevation, Fig. 2 a plan or top view, and Fig. 3 a side elevation, of a bath-tub embodying my design.

In plan view, or looking down upon the tub 20 from above, the outline of the tub is in form of a parallelogram having rounded ends *a a*. In both side and end view the tub slopes from the upper edge, *A*, inwardly to the bottom *B*, and

the bottom rounds into the sides and ends, as at *b b*. The bottom *B* is slightly depressed at 25 the center, and at that point an annular flange, *c*, is formed, as shown.

The leading feature of my design consists in the form of the tub, as seen in plan view, and the sloping sides and ends having rounded 30 lower edges.

I claim—

The design for a bath-tub herein described, and illustrated in the accompanying drawings, and consisting of the upper edge, *A*, having 35 straight sides and semicircular ends, the body portion *a* corresponding in shape to said edge, sloping in toward the bottom, and having rounded lower curves, *b b*, as set forth.

In testimony that I claim the foregoing I 40 have hereunto set my hand.

FRANCIS J. TORRANCE.
